UNITED STATES PATENT OFFICE.

LEWIS CLAYTON HILL, OF BIRMINGHAM, MICHIGAN, ASSIGNOR TO THE MURRAY CORPORATION OF AMERICA, OF DETROIT, MICHIGAN, A CORPORATION.

DESIGN FOR A COMBINED VEHICLE BODY AND HOOD.

Application filed May 21, 1928. Serial No. 26,775. Term of patent 7 years.

To all whom it may concern:

Be it known that I, LEWIS CLAYTON HILL, a citizen of the United States, and resident of Birmingham, in the county of Oakland, State of Michigan, have invented a new, original, and ornamental Design for Combined Vehicle Body and Hood, of which the following is a specification, reference being had to the accompanying drawing, forming a part thereof.

Fig. 1 is a side elevation of a combined vehicle body and hood, showing my new design.

Fig. 2 is a front elevation of a combined vehicle body and hood, showing my new design.

Fig. 3 is a rear elevation of a combined vehicle body and hood, showing my new design.

I claim:

The ornamental design for a combined vehicle body and hood as shown.

LEWIS CLAYTON HILL.
